UNITED STATES PATENT OFFICE

135,407

DESIGN FOR AN AMUSEMENT APPARATUS

John F. Meyer, Chicago, Ill., assignor to The Exhibit Supply Company, Chicago, Ill., a corporation of Illinois

Application November 23, 1942, Serial No. 108,838

Term of patent 7 years

To all whom it may concern:

Be it known that I, John F. Meyer, a citizen of the United States and a resident of Chicago, in the county of Cook and State of Illinois, have invented a new, original, and ornamental Design for an Amusement Apparatus, of which the following is a specification, reference being had to the accompanying drawing, forming a part thereof, and in which:

Fig. 1 is a perspective view of an amusement apparatus showing my new design;

Fig. 2 is a side elevational view of the same as seen from line 2—2 in Fig. 1; and

Fig. 3 is a horizontal sectional view of the same as seen from line 3—3 in Fig. 2.

I claim:

The ornamental design for an amusement apparatus, as shown.

JOHN F. MEYER.
